SPIRAL SWING

Clarence K. Harris, Marion, Ohio

Application December 12, 1933, Serial No. 702,076

11 Claims. (Cl. 272—33)

My invention relates to play and exercise equipment and particularly to spiral swings.

An object of my invention is to provide a spiral swing that shall be so constructed that it can be kept in continuous cyclic operation.

Another object of my invention is to provide a spiral swing that shall have relatively few parts and be easily manufactured and set up for operation.

Other objects of my invention will either be apparent from the description of one embodiment of my invention now preferred by me or will be specifically pointed out hereinafter.

In practicing my invention, I provide a base, a vertically extending standard thereon, a platform or cross bar slidable and turnable on the standard, and a rope or cable to support the platform from the top of the standard. I provide a pair of lever arms pivotally mounted on the platform near the respective ends thereof, each lever arm having a shorter portion located below the platform and a longer portion thereof located above the platform. The ends of the cable are connected to the lever arms intermediate their ends but above the platform. A member of cone shape is located on the standard below the upper end thereof.

In the single sheet of drawing,

Figure 1 is a view, in side elevation, of a device embodying my invention, certain portions thereof being shown in section,

Fig. 2 is a top plan view of the device shown in Fig. 1,

Fig. 3 is a view in end elevation, of a part only of the device, and,

Fig. 4 is a view mainly in vertical section through the top of the standard.

My device embodies a base which may consist of two crossed bars 11 and 13, the midportions thereof interfitting with each other, the outer ends of each bar being provided with spacer blocks 15. A metal plate 17, which may be of suitable shape and dimensions may be provided at the intersection of the two bars 11 and 13 and be secured thereto in order to strengthen the base.

A vertically extending standard 19 in the form of a pipe is fixedly supported by the base at the intersection of the bars 11 and 13 and for this purpose an annular flanged member 21 may extend through the plate 17 and the bars 11 and 13, and be secured thereto in any desired manner, the primary object being to hold the standard 19 in a substantially vertical upright position.

A cap member 23 is located at the top of the standard 19. The cap member is provided with

a depending cylindrical portion 25 fitting closely in the upper end of pipe 19, which upper end may be provided with a recess 27 to receive a projection 29 on cap 23 so that the cap will be prevented from turning relatively to the pipe. The upper end portion of member 23 may be made of lozenge shape, as is shown in Fig. 2 of the drawing, and be provided with two inclined openings 31 and 33 spaced apart from each other sufficiently so that their lower ends will be outside of the standard 19.

A rotatable platform or cross bar 35 is in the shape of a board or plank, the outer ends of which extend beyond the base. While I have described the platform 35 as being a plank I do not wish to be restricted thereto as I may use any other form of platform as will be more fully pointed out hereinafter. The outer ends of the cross bar 35 are longitudinally slotted as shown at 37 and seats 39 for riders are adjustably mounted on the cross bar 35 near the outer ends thereof. I have shown an adjusting and clamping means in the form of a bolt 41 and a wing nut 43 thereon extending through a seat 39 and one of the slots in the cross bar 35. I may also provide a pin 45 spaced from the bolt 41 so as to maintain the seat 39 in its proper operative position on the cross bar 35 near one end thereof after its position has once been adjusted. It is obvious that the adjustable feature of the seats will make it easy to operate my play and exercise device in a proper manner even if the weight of the players be different one from the other.

The cross bar 35 is further provided at a suitable point intermediate its outer ends and its midportion with recesses 49, which may be of substantially rectangular shape and extend longitudinally thereof. A bearing member 51 is suitably secured to the under side of the cross bar at each one of the recesses 49 and is so constructed that a laterally extending pivot pin 53 may be located therein and held thereby. On this pivot pin there is mounted a lever arm 55 and it is to be understood that two such lever arms are provided, as is clearly shown in Fig. 1 of the drawing. A stirrup or foot bar 57 is provided for each lever arm 55 and is secured thereto at the lower end thereof. I wish to point out particularly that the pivot pin 53 extends through the lever arm 55 at a point intermediate the ends of the lever arm, and that the shorter portion of the length of each lever arm is located below the cross bar 35, while the greater portion of the length of each lever arm is located above the cross bar.

I provide a pair of short hand ropes 59, the midportion of a single rope being fixedly connected to

- an eye bolt 61 connected or secured to the upper end of lever arm 55. It may be pointed out here that bar 57 is to be engaged by the feet of a player sitting on a seat adjacent to the lever arm,
- 5 while the ropes 59 are to be grasped by the hands of the player, for a purpose to be hereinafter more fully set forth. In order to prevent tilting or lateral movement of the lever arms 55 on the pivot bolt 53 I may provide metal strips 63, one at each
- 10 side of each lever arm 55, one end of each strip being connected to the lever arm as by a bolt 65, while the other ends of each pair of strips may have engagement with the pivot bolt 53.

Means for supporting the cross bar or platform 35 from the top of the standard may comprise a cable or rope 67, the midportion of which engages the cap member 23 and extending through the respective openings 31 and 33 therein or individual lengths of ropes may be used, the upper 15 ends of which are secured to hooks at the top of the standard. The ends of the rope or cable are suitably secured to the respective lever arms 55 at a point intermediate the ends thereof, but above the cross bar 35. Such connection may be 20 made by means of an eye bolt 69 and a cooperating nut 71 thereon.

I provide also a member 73 of cone shape on the standard 19 immediately below the upper end thereof, and the member 73 is held in a fixed 25 position on the standard 19 by a pin 75. The purpose of this member will be more fully described hereafter.

The object of players seated on the seats 39 at the ends of cross bar 35 is to maintain a rotary motion of the platform 35 first in one direction, whereby the rope or cable 67 is wound spirally around the upper end of standard 19 and on the cone 73, the platform being raised vertically upwardly thereby, and then in the other direction 30 whereby the cable is unwound and the platform moves vertically downwardly on the standard. To accomplish this object and to start the operation of the device the players will first walk the cross bar 35 several times around the standard 19 and will then quickly mount their respective seats using the stirrups 57, after which they immediately grasp the hand ropes 59 pulling thereon and simultaneously pushing on the stirrups 57 so that the lever arms 55 will tend to move pivotally on 35 the cross bar 35 with the upper ends thereof moving outwardly. This movement of the two lever arms will cause the horizontal cross bar 35 and the riders to rise a small distance vertically upwardly, thereby increasing the potential energy 40 of the moving parts of the device. The rotative movement of bar 35 and its vertical upward movement continue but with a decreasing speed.

The rope is first wound spirally around the extreme upper end of the standard and then around 45 the member 73 of cone shape. The retarding action on the moving parts is slightly increased by the use of the cone shaped member 73 as it increases the radius of the part around which the rope is wound. The use of the cone shaped member 50 also has the result that a greater length of rope is wound up for each complete turn of the platform 35 and that the platform is raised through a greater distance than at the beginning 55 per complete turn of the rope around the standard.

The cross bar 35 will come to a momentary stop and will then immediately begin to rotate in the other direction to unwind the rope. The cone shaped member then acts to increase the 60 accelerating force during the initial moments of

reverse operation, that is when the rope begins to unwind so that the platform 35 rotates rapidly very soon after starting to turn to unwind the rope.

The horizontal bar 35 and the riders thereon will now turn around the standard 19 in a direction opposite to that in which they were turning before, so that as stated above the rope 67 is unwound from the cone shaped member 73 and the standard 19. It is to be understood that the 10 riders have held the lever arms 55 in their outermost position, as is shown more particularly by the broken lines in Fig. 1 of the drawing, which may be considered as showing the position of the 15 rope, the lever arms, and the horizontal bar at the instant of momentary cessation of motion.

The rotary movement of the bar 35 will of course increase as the rope is unwound and the cross bar 35 is lowered relatively to the standard 19. At the instant when the cross bar 35 reaches 20 its lowermost position with the lever arms 55 in their adjusted position, that is with the upper ends outwardly as shown by the broken lines, the lever arms 55 are released by the riders so that 25 they will momentarily take the positions substantially as shown in Fig. 1 of the drawing. This decreases the angle between the cable and the standard and at the same time decreases the strain in the cable. This variation in the angles of support and the differences in the strain in the cable has been found to be fully sufficient to completely rewind the cable upon the standard in the same direction as was first described. It is to be noted also that a certain amount of the potential 30 energy stored in the moving system was released 35 by the release of the lever arms and their return to the position shown by the full lines in Fig. 1 of the drawing.

It is to be noted further that rewinding of the 40 cable starts on the smallest diameter, that is, that of the standard, at a time when the swing has its maximum momentum, which momentum is gradually diminished until the moving parts are again momentarily at rest. It is of course to be understood that during the time of rewinding 45 the cable on the standard, the riders will again move the lever arms 55 pivotally relatively to the cross bar 35 at the proper time, in the manner first above set forth.

It may be noted that several devices of the kind 50 herein shown and described have been tried out in actual operation, and it has been found easily possible to maintain continuous cyclic operation thereof for as long a time as desired by the players or riders. The spiral swing never attains 55 enough speed to be dangerous, since it comes to a momentary full stop at the top of its vertical travel. Its maximum rotative speed is attained at the instant when it reaches the bottom point of its vertical travel, this speed having been found 60 sufficient to cause full rewinding of the cable on the standard. The amount of effort required by the riders is not excessive, and in general the weight of the riders is in proportion to the 65 muscular strength exertable by the riders to maintain the device in motion. The action of the device embodying my invention is snappy and calls into action the muscles of the arms, legs, and back.

While I have shown a cross bar in the form of 70 a plank, I do not wish to be restricted thereto as this will seat two riders only. It is obvious that the cross bar 35 may be made in the form of a member of star shape, or of circular shape, 75

whereby a larger number of riders may be accommodated at any one time.

Various modifications may be made in the device embodying my invention without departing from the spirit and scope thereof, and I desire therefore that only such limitations shall be placed thereon as are imposed by the prior art or are set forth in the appended claims.

I claim as my invention:—

1. In a spiral swing, the combination with a base, a vertical standard thereon, a platform slideable and rotatable on the standard, vertically extending lever arms pivoted intermediate their ends to the platform adjacent the ends thereof, a cable having its mid-portion secured to the top of the standard and its ends secured to points on the respective lever arms intermediate their ends and above the platform, and means on the respective lever arms to effect manual actuation thereof at points both below and above the platform.

2. In a spiral swing, the combination with a base, a vertical standard thereon, a platform slideable and rotatable thereon, vertically extending lever arms pivoted intermediate their ends to the platform adjacent the two ends thereof, a cable having its mid-portion secured to the top of the standard and its ends secured to points on the respective lever arms above the platform and means on the respective lever arms to effect manual actuation thereof to increase the potential energy stored in the platform.

3. In a spiral swing, the combination with a base, a vertical standard thereon, a platform slideable and rotatable on the standard, vertically extending lever arms pivoted intermediate their ends to the platform adjacent the two ends thereof, a cable having its mid-portion secured to the top of the standard and its ends secured to points on the respective lever arms above the platform and means on the respective lever arms to effect operation thereof by riders on the platform to increase the potential energy stored in the rotatable platform at a certain position thereof on the standard.

4. In a spiral swing, the combination with a base, a vertical standard thereon, a platform slideable and rotatable on the standard, ropes having their upper ends secured to the top of the standard and means connecting the lower ends of the ropes to the platform manually operable to increase the amount of potential energy stored in the platform.

5. In a spiral swing, the combination with a base, a vertical standard thereon, a platform slideable and rotatable thereon, seats for riders on the platform adjustably secured to the platform at the respective ends thereof, lever arms pivotally secured to the platform intermediate their ends, a cable having its mid-portion secured to the top of the standard and its ends secured to the lever arms and means for manual actuation of the lever arms including a foot bar at the lower end of each lever arm and a hand rope at the upper end thereof whereby the potential energy of the platform is increaseable by the riders on the platform in timed synchronism with its cyclic movements to maintain the platform in continuous operation.

6. In a spiral swing, the combination with a base, a standard thereon, a platform slideable and rotatable on the standard, a cable having its mid-portion secured to the top of the standard and its ends operatively secured to the platform adja-

cent the ends thereof and adapted to be wound around the standard as the platform rotates therearound and a cone shaped member encircling the standard to receive a part of the wound-up cable on its surface.

7. In a spiral swing, the combination with a base, a standard thereon, a platform slideable and rotatable on the standard, a plurality of cables having their upper ends secured to the top of the standard and their lower ends operatively secured to the platform adjacent the ends thereof and adapted to be wound around the standard as the platform rotates and cause a predetermined vertical sliding movement of the platform relatively to the standard for each complete turn of the platform around the standard and means on the standard below the upper end thereof to vary the amount of vertical sliding movement of the platform on the standard per complete turn thereof.

8. In a spiral swing, the combination with a base, a vertical standard thereon, a platform slideable and rotatable on the standard, a cable having its mid-portion secured to the top of the standard and its ends operatively secured to the platform adjacent to the ends thereof and adapted to wind a predetermined amount of cable on the standard per complete turn therearound and means on the standard to increase the amount of cable wound around the standard per complete turn of the cable thereon upon the termination of the winding of a predetermined amount of cable on said standard.

9. In a spiral swing, the combination with a base, a vertical standard thereon, a platform slideable and rotatable on the standard, vertically extending lever arms pivoted intermediate their ends to the platform adjacent the ends thereof, a cable having its mid-portion secured to the top of the standard and its ends secured to the respective lever arms intermediate their ends and above the platform and adapted to be wound around the standard as the platform rotates and a cone encircling the standard and of larger diameter than the standard to receive a part of the wound-up cable.

10. In a spiral swing, the combination with a base, a vertical standard thereon, a platform slideable and rotatable on the standard, a cable having its mid-portion secured to the top of the standard and its ends operatively secured to the platform adjacent to the ends thereof and adapted to wind a predetermined amount of cable on the standard at a predetermined rate per complete turn therearound and means on the standard to increase the amount of cable wound around the standard per complete turn of the cable thereon upon the termination of the winding of a predetermined amount of cable on the standard.

11. In a spiral swing, the combination with a base, a vertical standard thereon, a platform slideable and rotatable on the standard, a cable having its mid-portion secured to the top of the standard and its ends operatively secured to the platform adjacent to the ends thereof and adapted to wind a predetermined amount of cable on the standard per complete turn therearound and means on the standard to progressively increase the amount of cable wound around the standard per complete turn of the cable thereon upon the termination of the winding of a predetermined amount of cable on the standard.

CLARENCE K. HARRIS.
